I. E. BRADY.

STANDARD FOR FLAT CARS.

APPLICATION FILED APR. 11, 1917.

1,231,843.

Patented July 3, 1917.

UNITED STATES PATENT OFFICE.

ISAAC E. BRADY, OF HOPE MILLS, NORTH CAROLINA, ASSIGNOR OF ONE-HALF TO
EUGENE H. GAINNEY, OF HOPE MILLS, NORTH CAROLINA.

STANDARD FOR FLAT-CARS.

1,231,843.

Specification of Letters Patent.

Patented July 3, 1917.

Application filed April 11, 1917. Serial No. 161,319.

To all whom it may concern:

Be it known that I, ISAAC E. BRADY, a citizen of the United States, residing at Hope Mills, in the county of Cumberland 5 and State of North Carolina, have invented certain new and useful Improvements in Standards for Flat-Cars, of which the following is a specification.

My invention relates to adjustable standards for flat-cars.

An important object of the invention is to provide a standard of the above mentioned character, embodying telescoping members, adapted to be elevated above the 15 floor of the flat-car for a substantial distance, and when collapsed or folded to lie wholly below such floor, thus not interfering with the loading or unloading of the car.

A further object of the invention is to 20 provide means for binding the load to the flat-car, such means being adapted to be carried in certain of the tubular sections of the standards.

A further object of the invention is to 25 provide means of the above mentioned character, which are simple in construction, inexpensive to manufacture, strong and durable.

Other objects and advantages of the invention will be apparent during the course 30 of the following description.

In the accompanying drawings forming a part of this specification, and in which like numerals are employed to designate like parts throughout the same,

35 Figure 1 is an end elevation of the flat-car, showing my adjustable standards secured thereto,

Fig. 2 is an enlarged side elevation of one standard,

40 Fig. 3 is an elevation of the inner side of the standard, taken at a right angle to Fig. 2, with the lower portion thereof broken away,

Fig. 4 is a longitudinal sectional view 45 taken on line 4—4 of Fig. 3,

Fig. 5 is a similar view taken on line 5—5 of Fig. 2,

Fig. 6 is a horizontal sectional view taken on line 6—6 of Fig. 3,

50 Fig. 7 is a similar view taken on line 7—7 of Fig. 3, and,

Fig. 8 is an elevation of the outer side of the standard, showing the members thereof collapsed.

55 In the drawings, wherein for the purpose

of illustration is shown a preferred embodiment of the invention, the numeral 10 designates the body portion of a flat-car, having a top 11, as shown.

Arranged upon the opposite sides of the 60 body portion 10 are sockets 12, having attaching flanges 13, provided with openings 14. The sockets 12 have flanges 15, receiving therebetween U-bolts 16, extending through the openings 14, and attached or 65 anchored to the sides of the body portion 10.

Each standard comprises a plurality of telescoping sections 17, 18 and 19, which are tubular, as shown. The lower tubular section 19 is mounted to slide or telescope within the 70 socket 12, and is provided with a laterally extending pin or member 20, to project into an inverted U-shaped opening 21, formed in the socket 12. One arm of the opening 21 leads into an interior groove 22, which extends through the bottom of the socket, and adapted to allow the pin 20 to pass therebelow, so that the tubular section 19 may be moved to the lowermost position, which is defined by an annular flange 23, formed 75 upon the upper end thereof, contacting with the top of the socket. The tubular section 18 has its lower end closed by a head 24, and this lower end is mounted to slide in the tubular section 19. The tubular section 18 80 carries a laterally projecting pin or member 25, adapted to operate in a longitudinal slot 26, formed in the tubular section 19, such slot having an inverted U-shaped portion 27 at its upper end. It is apparent that 85 when the pin 25 is in the closed end of the inverted U-shaped slot portion 27, the tubular section 18 will be locked in the upper position, but when this pin is in the slot 26 proper, the tubular section 18 is free to be 90 moved downwardly into the tubular section 19, until its flanged upper end 28 contacts with the flange 23. As before stated, the lower end of the tubular section 18 is 95 closed by the head 24, thus providing a 100 pocket 29, beneath a horizontal partition 30, fixed to the interior of the tubular section 18, for the reception of a chain 31 or other flexible binding element. One end of this chain is anchored, by suitable means, to 105 the bottom 24, while its free end is adapted to be detachably secured in a slot or key-hole opening 32, formed in the partition 30. The tubular section 18, as clearly shown in 110 Fig. 3, is provided with a longitudinally ex-

tending slot 33, communicating with the chamber 29, and with a laterally extending opening 34, arranged above the partition 30, for a substantial distance. When the chain 5 is in use it is passed through the opening 34, and held thereby against downward displacement, and the function of the slot 33 is to provide means whereby the chain may be attached to the tubular section 18 at a point 10 substantially equidistantly spaced from the two ends of the standard, when the tubular sections thereof are longitudinally distended. The tubular section 17 has its bottom closed, as shown at 35, for the reception 15 of a chain 36 or other flexible binding element, adapted to be stored therein when not in use. The tubular section 17 is provided with a laterally extending pin or member 37, adapted to operate in a longitudinal slot 38, 20 formed in the tubular section 18, and in an inverted U-shaped portion 39 of the slot. It is thus apparent that when the pin 37 is in the closed end of the inverted slot portion 39, the tubular section 17 will be locked 25 in the upper position, and by moving the pin 37 into the slot 38 proper, the tubular section 17 may be lowered into the tubular section 18, until its closed flanged end 40 contacts with the flange 28. The chain 36 is 30 passed from the upper end of the tubular section 17 through an opening 41, and the free end of the chain is adapted to be secured in an opening or key-hole slot 42, formed in a partition 43, which is fixed to 35 the interior of the tubular section 17.

The operation of the apparatus is as follows:

When the tubular sections 17, 18, and 19, are collapsed, as clearly shown in Fig. 8, 40 the upper ends thereof are disposed wholly beneath the top of the body portion 10, in no way interfering with the loading or unloading of the flat-car. After the car has been partly or wholly loaded, as illustrated 45 in Fig. 1, the tubular sections 17, 18, and 19, are moved to the upper positions, and locked therein, as is obvious. The chains 31 are withdrawn from the tubular sections 18 and hooked over the shoulders of the 50 openings 34, such chains having their free ends connected, by any suitable means, as illustrated in Fig. 1. In a similar manner, the chains 36 may be withdrawn and their free ends connected. 55 It is to be understood that the form of my invention herewith shown and described

is to be taken as a preferred example of the same, and that various changes in the shape, size, and arrangement of parts may be resorted to without departing from the spirit 60 of the invention or the scope of the subjoined claims.

Having thus described my invention, I claim:

1. An adjustable standard for a flat-car, 65 comprising a sleeve to be secured to the side of the flat-car and having an L-shaped opening and a longitudinal opening communicating therewith, means to attach the sleeve to the side of the car, a plurality of telescoping tubes adapted to be moved longitudinally within the sleeve and having L-shaped openings and longitudinal openings 70 communicating therewith, a lateral extension secured to one tube and adapted to operate 75 within the L-shaped opening of the sleeve, and lateral extensions secured to the remaining tubes and adapted to operate within the L-shaped openings of the adjacent tubes.

2. An adjustable standard for a flat-car, 80 comprising a vertical sleeve rigidly attached to the side of the flat car beneath the floor thereof and having an L-shaped opening and a longitudinal opening communicating therewith, a plurality of telescoping 85 tubes adapted to be moved longitudinally within the sleeve and having L-shaped openings and longitudinal openings communicating therewith, an annular flange secured to each tube adjacent its upper end, a lateral 90 extension secured to the lower end of the lowermost tube and adapted to operate within the L-shaped opening of the sleeve, and lateral extensions secured to the lower ends 95 of the remaining tubes and adapted to operate within the L-shaped openings in the adjacent tubes.

3. An adjustable standard for a track-car or the like, comprising a tubular section to be connected with the car, a second tubular section mounted to slide within the first named tubular section and having its lower end closed and provided with an opening extending through the side thereof, and a flexible binding element arranged within the 100 closed lower end of the second named tubular section, and having its free end adapted to be passed through said opening.

In testimony whereof I affix my signature.

ISAAC E. BRADY.
